UNITED STATES PATENT OFFICE.

WILLIAM L. CARD, OF LA CROSSE, WISCONSIN, ASSIGNOR TO THE TIERRA SECA MINING COMPANY, OF EAST ST. LOUIS, ILLINOIS.

CRUSHING OR PULVERIZING MILL.

SPECIFICATION forming part of Letters Patent No. 372,742, dated November 8, 1887.

Application filed July 22, 1886. Serial No. 208,800. (No model.)

To all whom it may concern:

Be it known that I, WILLIAM L. CARD, a citizen of the United States, residing at La Crosse, in the county of La Crosse and State 5 of Wisconsin, have invented certain new and useful Improvements in Mills for Crushing and Pulverizing; and I hereby declare the following to be a full, clear, and exact description of the same, reference being had to the accompanying drawings, wherein—

Figure 1 is a plan or top view of a crusher and pulverizer embodying my invention. Fig. 2 is a side elevation of the same. Fig. 3 is a vertical section on the line 3 3, Fig. 1. Fig. 4 15 is a longitudinal section of the roller on the line 4 4, Fig. 3. Fig. 5 is a detached longitudinal section of one of the concave sections, taken on the line 5 5, Fig. 7. Fig. 6 is a rear perspective view of one of the concave shoes 20 detached. Fig. 7 is a face view of one of the concave sections, showing the slots by which the shoe is secured. Fig. 8 is a cross-section of the concave section and shoe combined on the line 8 8, Fig. 3. Fig. 9 is a detailed section of one end of the roller, showing liners 25 inserted beneath the detachable bars which form the ribs of the roller.

Like letters refer to like parts wherever they occur.

30 My present invention relates to the construction of crushing and pulverizing mills generally, but especially to that class which are used for crushing and pulverizing placer-earth and like material preparatory to the elimination 35 of the precious metal, and has for its objects to cheapen and simplify the construction, to render the machine more durable, and when worn more easily and quickly repaired, than is any machine of this class as now constructed.

40 These features of ready renewal of the parts when worn and the prolongation of the life of the wearing-surfaces are very important in the rough and unsettled districts where placer-mining is carried on. To obtain these results 45 I form the body of the roller of cast-iron or other suitable material, and with longitudinal grooves for the reception of steel bars, which project beyond the face of the roller to form the crushing and pulverizing ribs, which coact 50 with the concave; and the concave I form of

sections, preferably narrow sections, having slots for the reception of lugs on the backs of the wearing-shoes, the shoes being preferably of such character that they can be reversed.

I will now proceed to describe my invention 55 more specifically, so that others skilled in the art to which it appertains may apply the same.

In the drawings, A indicates suitable uprights with cross-pieces a a', constituting a frame for the machine, in which frame is supported a hopper, B, a roller, C, and a concave, D, inclosed by a suitable casing, E, with discharge-orifice e.

The roller C, I construct with a body, c, of cast-iron or other suitable material, said body 65 having longitudinal grooves, in which are secured steel bars c', of such width as will give the desired height of rib on the surface of the roller, and said bars c' are secured by flanged or cup-shaped caps c'', one or both of which may 70 be detachable, and which may also constitute the journals of the roller.

It will be found convenient to make the shaft c' of the roller from a wrought-iron rod, then cast the body c of the roller thereon, and then 75 cut the longitudinal groove for the reception of the bars. The bars c' can be cut to length from merchant bar-steel, readily procured in the market, and the caps may be secured by pins c'', or in any other suitable manner, Fig. 9. 80

77 indicate liners, which are inserted in the longitudinal grooves of the roll-body C, beneath the bars c', so as to increase the projection of said bars from time to time, as desired, to increase the feed of the material or 85 to compensate for wear of the bars.

The concave D is formed of a series of sections, d, preferably narrow, as shown in Figs. 1, 5, 7, and 8, with concave faces having slots d', narrower below than above, and with ribs 90 or flanges d'' on the back, by which means strength and lightness are both obtained. To form the concave which coacts with the roller, a series of these sections d are pivoted on a transverse rod, as at f, with their heel-pieces 95 d'' projecting rearwardly over the cross-timber a' of the frame, (or over other suitable support,) and said sections are held up to their work by suitable springs—as, for instance, the spiral springs h, which bear on the heels d''. 100

Each spring encircles a bolt, H, which passes through a bolt-hole in the heel of the section d, and is secured by a nut, h', below the cross-timber a' of the frame. In order to adjust the 5 sections d of the concave D, a lag-screw, g, is arranged in the cross-timber a', below the heel of each section d. The sections d, constituting the concave, are each shod with a shoe, G, which is cast preferably from hard gray iron, 10 and as only about one-third (more or less) of the shoe is subjected to hard wear, I double the life of the shoe by making it so that it can be detached from the concave and turned end for end and replaced when it becomes necessary. In order to do this I cast lugs g' upon 15 the back of the shoe in such position and of such shape that they will enter the wide and wedge in the narrow portions of the slots d' of the section d.

20 The construction being of substantially the character hereinbefore specified, the following advantages will result: The amount of material passing through the machine in a given time can be increased by inserting liners l below 25 the bars c', so as to increase their projection; or the same can be decreased by withdrawing the liners and allowing the rib-bars c' to recede into the body of the roll, and liners l may also be inserted from time to time as the faces of

the bars c' are worn, to compensate for wear 30 and enable the greater portions of the bars to wear away without interfering with the thorough work of the mill. As before specified, the shoes G can be reversed for the same purpose. When the liners are inserted beneath 35 the bars, the ends of the bars should be slightly filed to allow the replacing of the caps c'. The bars c', when no longer wide enough to be used with liners, may be removed and replaced by bars of proper length cut from ordinary merchant bar-steel. 40

Having thus set forth the nature and advantages of my invention, what I claim, and desire to secure by Letters Patent, is—

In a crushing and pulverizing mill, the combination, with a concave section having slots narrower below than above, of a reversible shoe having lugs upon its back, said lugs adapted to lock in the slots of the concave section, substantially as and for the purposes 45 50 specified.

In testimony whereof I affix my signature, in presence of two witnesses, this 21st day of July, 1886.

WILLIAM L. CARD.
